UNITED STATES PATENT OFFICE

2,641,846

WALL ALIGNMENT APPARATUS

Manuel Zeno, Santurce, P. R.

Application February 14, 1950, Serial No. 144,153

1 Claim. (Cl. 33—85)

1

This invention relates to the class of masonry and concrete structures, and more particularly to an apparatus for use when constructing a wall of concrete blocks or cement aggregate blocks, the apparatus being especially adaptable for use in obtaining a true vertical surface for the masonry wall.

An object of the invention is to provide an apparatus for properly lining up building blocks so as to enable them to be constructed into a masonry wall in a true vertical surface.

A further object of the invention is to provide a wall alignment apparatus which will have an alignment member having a straight edge, which alignment member can be raised or lowered readily and which will remain horizontal and plumb after the apparatus has once been set up and trued without the necessity of a truing operation whenever the straight edge is raised or lowered.

Another object of the invention is to provide a wall alignment apparatus which is readily portable and may be moved from one location to another in a manner similar to that of pushing a wheelbarrow.

Still further objects of the invention reside in the provision of a wall alignment apparatus that is strong, durable, highly efficient in operation, simple in construction and manufacture, capable of aiding in the construction of a wall with true vertical surfaces, provided with a shelf for raising and lowering building blocks, and which is relatively inexpensive.

These, together with the various ancillary objects of the invention which will become apparent as the following description proceeds, are attained by this wall alignment apparatus, a preferred embodiment of which has been illustrated in the accompanying drawings, by way of example only, wherein:

Figure 1 is a perspective view of the wall alignment apparatus shown in operative use while constructing a masonry wall;

Figure 2 is a vertical sectional view as taken along line 2—2 in Figure 1; and

Figure 3 is a sectional detail as taken along line 3—3 in Figure 1 and showing the means for maintaining the aligning member of the present invention in horizontal plane.

With continued reference to the accompanying drawings, wherein like reference numerals designate similar parts throughout the various views, reference numeral 10 generally designates the alignment apparatus comprising the present invention. This wall alignment apparatus provides an aid to the mason or bricklayer in truing the

vertical walls of the building or structure on which he is working.

As shown in the drawings, the device is especially adaptable for use in making masonry walls from concrete building blocks or other cement aggregate blocks.

The wall alignment apparatus 10 comprises a pair of vertical standards 12 and 14 placed in parallel vertical relation to each other and secured together at their upper ends by a horizontal beam or bar 16. The standards 12 and 14 are supported on a substantially rectangular or square base frame which is composed of members 18, 20, 22 and 24. Journaled in the member 18 is a pair of wheels 26 and 28 for aiding in the transportation of the wall alignment apparatus from one location to another. The apparatus becomes portable by merely lifting the member 22 and pushing the entire apparatus forward, the apparatus thus acting in the manner of a wheelbarrow.

A pair of rigidifying beams 30 and 32 secure members 18 and 22 and extend transversely between them and abut the standards 12 and 14, respectively. A pair of bracing members 34 and 36 are terminally secured to the standards 12 and 14 and the beams 30 and 32 respectively. A further rigidifying element 38 extends transversely between the beams 30 and 32 and abuts against the braces 34 and 36.

Secured to the member 22 at each end thereof are bearing nuts 40 and 42 within which leveling screws or legs having suitable ground-engaging and handle means thereon are threadedly employed. The screws are designated by reference numerals 44 and 46.

Threadedly engaged in the center of the beam 16 is a hook 48 which supports a pulley wheel 50 of conventional design. A hook 52 is secured to member 18 in a position eccentrically disposed from the center of the member 18. Secured to the hook in a detachable manner is one end of a cable which is passed through the pulley wheel 50. The cable is designated by reference numeral 54, and may be readily made from manila or hemp or other suitable material, as desired. The other end of the cable 54 is secured on a hook 56 which is bolted to a shelf plate 58 which forms one part of the aligning member. The plate 58 abuts against and is secured to a vertical aligning plate 60 which is adapted to be the vertical guide for the building blocks. Secured to the plate 60 and extending inwardly therefrom are two sets of two opposed pairs of embracing lugs or guides 62 and 64 which embrace the standards 12 and 14. As the aligning member is raised or lowered by means

of the cable and the pulley wheel 50 and when in engagement with the masonry wall, the plate 58 will abut against a vertical surface of the posts and the embracing lugs will prevent rotation of the plate relative to the horizontal and to the standard centers 12 and 14. Because of the offset of the cable 54, the aligning member may be more readily controlled. It is to be noted that the building blocks may be raised by shelf plate 58 so as to be readily available to the mason using the invention.

In operation, the wall aligning apparatus is placed in front of the outside face of the wall which it is desired to be constructed and is properly adjusted and anchored so as to level the frame. The aligning member is lowered to the base of the frame and is adjusted so that its surface will be flush with the outside of the first layer of building blocks. As the courses of blocks are laid, they are pushed against the plate 60 of the aligning member and thus will be automatically aligned in a correct location. When the second course of blocks is about to be placed, the aligning member is raised the desired amount and the blocks are then pushed against it. This operation is repeated with every course of building blocks.

It is obvious from the operation and construction of this wall aligning apparatus that the plate 60 will move in a true vertical plane flush with the outside face of a vertical wall. Since the building blocks are always laid in direct contact with the plate 60, the result will be a wall of true verticality and perfect horizontal alignment.

Since, from the foregoing, the construction and advantages of this wall alignment apparatus are readily apparent, further description is believed to be unnecessary.

However, since numerous modifications will readily occur to those skilled in the art after a consideration of the foregoing specification and

accompanying drawings, it is not intended to limit the invention to the precise embodiment shown and described, but all suitable modifications and equivalents, such as changes in size and shape or material, may be readily resorted to which fall within the scope of the appended claim.

Having described the invention, what is claimed as new is:

A block wall alignment apparatus comprising a horizontal base frame for positioning adjacent a wall, uprights rising from the forward end portion of said frame, a bar extending between the upper portions of said uprights, a pulley mounted on said bar, a straight edge engageable with the wall and including guides slidably engaged with the uprights, a cable trained over the pulley and connected to the straight edge for adjusting same vertically on the uprights, supporting wheels journaled on said forward end portions of the frame, and leveling legs threadedly mounted on the rear end portion of the frame for adjusting the straight edge toward or away from the wall.

MANUEL ZENO.
